ELECTRON TUBES

John H. O. Harries and Barbara K. Harries, Granaway, Warwick, Bermuda, assignors, by mesne assignments, to The Machlett Laboratories, Incorporated, Springfield, Conn., a corporation of Connecticut

Application July 30, 1957, Serial No. 675,080

5 Claims. (Cl. 313—69)

This invention relates to improvements in beam-forming electron tubes and has particular reference to pulsed beam tubes having novel electrode structures.

In conventional four-electrode tubes it is well known that the wires of a control grid intercept a sufficient amount of the electron discharge from the cathode as to cause undesirable grid current and resultant heating of the control grid and its supporting structure. Known previous attempts to overcome this problem have been based on knowledge that the control grid wires are bombarded by electrons traveling directly from the cathode to the control grid.

We have discovered that grid current is caused not alone by such direct bombardment of the grid wires but also by the return of electrons after they have passed the grid wires. In fact we find that the primary cause of grid current in beamed triodes having screening grids at cathode potential, or screening grids whose potential with respect to the cathode is substantially less than the control grid-to-cathode potential during the conductive part of the cycle, is due to returning electrons rather than to direct bombardment.

The present invention is directed to means for modifying the shape of the electric field in the cathode-anode space whereby the electron trajectories which were previously turned back toward the control grid are instead caused to be directed toward the anode. This is accomplished by providing the screen grid wires with radially extending fin-like cross-sectional shapes which not only direct the electrons from the cathode to the anode in the desired manner but also maintain a high value of mu and reduce the screen grid to anode capacity.

The present invention also relates to such a screen grid in combination with a cathode which is shaped to focus streams of electrons into beams and a control grid having effective portions positioned relatively close to the cathode and as close to the sides of the electron beams as is compatible with the beams not being directly intercepted by the control grid, with the radial fin-type screen grid being maintained at or near cathode potential and so spaced from the control grid and the anode that the screening factor or mu of the control grid is relatively high, and so that sufficient positive field from the anode penetrates between the two grids so as to draw the electrons toward the anode when the anode potential is in the range of one to three times the maximum positive potential at which the control grid is driven during operation of the tube.

Accordingly, a primary object of our invention is to provide an electron tube with a novel electrode structure which substantially reduces or eliminates undesirable grid current.

Another object is the provision in an electron tube of a screen grid having a predetermined shape which will form electric fields therearound which substantially reduce the turning back to the control grid of electrons emitted by the cathode.

Another object is to provide an electron tube with a

2

novel screen grid which will not only increase the flow of electrons from the cathode to the anode but will also maintain a high value of mu and reduce the screen grid-to-anode capacity.

5 A further object is to provide an efficient beamed triode having an additional novel screen grid of the above character.

Other objects and advantages of the invention will become apparent from the following description taken in 10 connection with the accompanying drawings, wherein:

Fig. 1 is an axial sectional view of the electrode structures of an electron tube embodying a preferred form of the invention;

Fig. 2 is a horizontal sectional view taken substantially 15 on line 2—2 of Fig. 1;

Fig. 3 is an enlarged fragmentary horizontal sectional view of a portion of the electrode structure;

Fig. 4 is a view similar to Fig. 3 illustrating a modified 20 cathode structure;

Fig. 5 is a diagrammatic view illustrating the trapping 25 of electrons by conventional grid structures and the prevention thereof by the present invention; and

Fig. 6 is a chart listing the various spacings and sizes 30 of electrode components in one successful tube embodying the invention.

Referring more particularly to the drawings, the electrode structures shown in Fig. 1 are adapted to be suitably mounted within an electron tube such as that shown and described in U.S. application Serial No. 690,356, filed October 15, 1957, and assigned to the common assignee, and for details of such tube structures as are not shown in the present drawings reference should be made to the copending application.

The electrode structures embodying the present invention include a cathode structure 10, a control grid structure 11, a screen grid structure 12 and an anode structure 13, all of which are coaxial structures mounted one within another as shown and suitably supported so as to maintain their respective predetermined space relations.

The cathode structure embodies a hollow cylindrical cathode 14 within which is located a heating coil or filament 15 (Fig. 2). The filament 15 is suitably connected to a source of electrical energy whereby it will radiantly heat the cathode 14 for liberation of electrons, as will be described. The outer surface of the cathode 14 is provided with a plurality of longitudinal grooves 16 which are spaced substantially equidistant apart throughout the circumference of the cathode. The side walls 17 of the grooves 16, in the preferred embodiment of this invention, 40 extend substantially radially with respect to the longitudinal axis of the cathode, and the bottoms of the grooves 16 are preferably slightly concave, being curved in a transverse direction as shown best in Fig. 2. Deposited upon the bottom of each groove 16 is a layer 18 of a selected 45 electron emissive material such as one of the oxides commonly used for this purpose in the electron tube industry. When the cathode is heated and a suitable potential applied in the normal manner across the tube, electrons are emitted by the material 18 and are caused 50 to flow in a direction toward the anode.

Opposite each land 19 between the respective grooves 16 is located a respective wire 20 of the control grid 11. The wires 20 extend parallel to the cathode and to each other and in predetermined spaced relation thereto, and 55 are of circular cross-sectional shape of a diameter consistent with the widths of the lands 19 such that the wires 20 are as close to the sides of the electron beams emanating from the emissive material 18 in grooves 16 as is compatible with non-interception of the beams by the 60 wires.

Radially spaced outwardly of each of the control grid wires 20 is a respective screen grid member or wire 21,

the wires 21 being located in predetermined spaced relations to both the anode 13 and wires 20.

The anode 13 is a hollow cylindrical body of copper which encloses the grids and cathode and forms in itself a large portion of the tube envelope.

The several electrodes are all supplied with various potentials by conductive means clearly shown and described in the aforementioned copending application. The tube is adapted to be operated by impressing the desired potential between the anode and cathode, applying a relatively high positive potential to the control grid, and applying to the screen grid a zero potential with respect to the cathode.

We have found that in an electron tube of the character described, the cross-sectional shape and the position of screen grid 12, in relation to the other electrodes and the anode, are very critical and assume particular importance in the consideration of the effect of the grids upon the "trapping" of electrons emitted by the cathode.

Known prior attempts to reduce or eliminate grid current caused by interception of electrons by the control grid have generally consisted of various methods of preventing direct bombardment of the control grid by electrons emitted by the cathode, such as by reducing the diameter of the control grid wires or removing the control grid wires far from the direct trajectories of the electrons. We have found that a very important cause of grid current is that of "trapped" electrons, that is, electrons which have passed between the wires of the control grid and are caused to be reversed back toward the control grid by the effect of the screen grid upon the field between the grids. Fig. 5 illustrates this undesirable feature where in a tube embodying conventional round-sectioned grid wires 20 and 22 some of the electrons from material 18 will follow trajectories 23 and 23a until they approach a screen grid wire 22. Then the field around wire 22 will reverse the directions of the electrons, causing them to assume new trajectories 24 and 24a whereupon they will collide with wire 20.

A tube of the presently described type is adapted to be operated by application to the control grid of a relatively high positive potential, and to the screen grid of a zero potential with respect to the cathode. Therefore, electrons emitted by the material 18 in the cathode grooves 16 will be focused, under the influence of the side walls 17 of the grooves, toward the anode 13. The control grid wires 20 are located just out of the direct trajectories of the electrons and, therefore, will not normally intercept the electrons. The curvature of the emitting surface also aids in properly focusing the electron beam because of the fact that electrons leave an emitting surface substantially normal to the surface at the point of emission.

In this type of tube structure, the positive control grid normally will not intercept any primary electrons until they have travelled past this grid and have reversed their directions and been trapped. Therefore, the control grid wires 20 may be conveniently of round cross-sectional shape, either single wires or pairs of radially disposed and closely adjacent round-section wires.

We have found, however, that the screen grid wires 21 should be provided with a particular predetermined cross-sectional shape which will form a shaped electrical field preventing a reversal of many of the electron trajectories. A flat or fin-like shape has proved to be very successful for this purpose. With a fin-shaped wire 21, many of the electron trajectories will not be reversed as in the case of a round-section wire, but instead will be permitted to continue on toward the anode, as indicated by the portions of the trajectories designated 25 and 25a in Fig. 5.

It is, of course, necessary that the fin-shaped grid wires 21 be strategically spaced from the control grid and from the anode, depending upon the potentials applied to these electrodes. The fin-shaped wires 21 should ex-

tend radially with respect to the center of the electrode structure, with one thin edge of each wire being directed toward the axis of the coaxial electrode structure. With such a structure, slight geometrical deviations as may occur in the manufacture of the tube will not cause significant ill effects such as are created upon even slight adjustments of round-sectioned wires. These considerations are based upon a static mu in the order of 100. A large increase of static mu will reduce anode to cathode potential gradient in areas between pairs of grid wires 21 and increase defocusing in these areas, thus tending to increase the possibility of trapping of electrons. Lower values of mu will, however, render trapping a less difficult problem.

Since the use of fin-shaped wires in the screen grid allows modifications in the sizes of other electrodes without resulting in changing the trajectories of the electrons emitted by the cathode, we have found that the diameter of the control grid wires may be increased and the inside radius of the anode 13 may be decreased, provided that the potentials of these electrodes are reduced to a predetermined figure. This results in a reduction in the driving power and an increase in the output efficiency, which are obtained by taking advantage of the concentric form of the equipotentials surrounding each wire 20 of control grid 11.

As stated hereinbefore, it is necessary that the electron streams from the cathode be focused, such as by the side walls 17 of grooves 16, in order to properly direct electrons so that they may be influenced by screen grid 12 in the proper manner. However, the actual focusing of the electrons may be accomplished by other cathode structures or shapes such as shown, for example, in Fig. 4 wherein the longitudinal grooves 26 in cathode 27 are transversely curved, with the curvature extending to substantially the outermost surface 28. The emitting material 29 is restricted to only the deeper portions of each groove 26 so that the uncovered or non-emitting portions 30 of the grooves will function to focus the electrons in a manner similar to the function of side walls 17 in Fig. 3. The lands 31 between grooves 26 may be provided with shallow transversely curved parallel longitudinal grooves which allow control grid wires 20 to be advantageously positioned closer to the cathode.

While the use of radial fin-type grid wires in various kinds of multi-grid tube structures is well known per se, we have found that fin-shaped wires may be successfully used in a screen grid for reducing "trapping" of electrons and reversal of the trajectories thereof toward a control grid in a tube having a high mu, when combined with a properly focusing cathode as taught herein.

It is to be understood, however, that various modifications may be made within the scope of the invention. Therefore, the details shown and described are to be interpreted as illustrative.

Referring particularly to Figs. 4 and 6, tubes have been satisfactorily made and operated when using an anode having an inside radius (a) of 1.440", a fin-shaped screen grid the wires of which are .020" thick and (c) .060" wide, and a control grid whose wires are (e) .070" in diameter. The cathode lands are grooved to a depth of (g) .015" and the control grid wires are located (f) .012" from the radius of the high points of the lands. The screen grid wires are (d) .025" from the control grid wires and are (b) .200" from the anode. The emitting groove of the cathode is (k) .020" deep and (h) .973" wide, with emitting material therein being (j) .055" wide. These tubes have a mu of between 90 and 100. It is pointed out here that the above dimensions are to be considered as approximate.

We claim:

1. In an electron tube, electrode structures comprising a hollow anode, a cylindrical cathode coaxial within the anode and having on its outer surface a plurality of alternately located electron emitting and non-emitting

areas and means for focusing electrons from the emitting areas into beams directed toward the anode, a control grid comprised of wires disposed adjacent to the non-emitting areas of the cathode, said cathode and anode being operable at different known potentials and the control grid being operable at a relatively high positive potential, and screen grid means located in predetermined spaced relation between the anode and control grid and comprised of members radially aligned with the wires of the control grid, said members being maintained during operation of the tube at substantially cathode potential and having cross-sectional shapes forming electric fields therearound which aid electron flow to the anode and prevent substantial trapping of electrons between grids.

2. In an electron tube, electrode structures comprising a hollow anode, a cylindrical cathode coaxial within the anode and having on its outer surface a plurality of alternately located electron emitting and non-emitting areas and means for focusing electrons from the emitting areas into beams directed toward the anode, a control grid comprised of wires disposed adjacent to the non-emitting areas of the cathode, said cathode and anode being operable at different known potentials and the control grid being operable at a relatively high positive potential, and a screen grid located in predetermined spaced relation between the anode and control grid and comprised of members radially aligned with the wires of the control grid, said members being adapted to be maintained during operation of the tube at substantially cathode potential and being ribbonlike in shape and extending parallel with the wires of the control grid and adapted at said potential to form electric fields therearound which aid electron flow to the anode and prevent substantial trapping of electrons between grids.

3. In an electron tube, electrode structures comprising a hollow anode, a cylindrical cathode coaxial within the anode and having on its outer surface a plurality of longitudinally extending parallel grooves separated by lands, the grooves containing supplies of heat effective electron emissive material, the lands being non-emissive, the sides of the grooves being substantially free of emissive material so as to aid in focusing electrons from the emissive material into beams directed toward the anode, a control grid comprised of wires disposed adjacent and parallel to the lands of the cathode, the wires being round-sectioned and of a diameter consistent with the widths of the lands such that the wires are as close to the sides of the electron beams as is compatible with non-interception of the beams by the wires, said cathode and anode being operable at different known potentials and the control grid being operable at a relatively high positive potential, and a screen grid comprised of members radially aligned with the wires of the control grid and adapted to operate at substantially the same potential as the cathode and having thin fin-like cross-sectional shapes forming at said potential electric fields therearound which aid electron flow to the anode and prevent substantial trapping of electrons between grids.

4. In an electron tube, electrode structures comprising a hollow anode having an inner surface of predetermined radius, a cylindrical cathode coaxial within the anode and having on its outer surface a plurality of longitudi-

nally extending parallel grooves separated by lands, the bottoms of the grooves containing electron-emissive material and the lands being non-emissive, the sides of the grooves being substantially free of emissive material so as to aid in focusing electrons from the emissive material into beams directed toward the anode, a control grid comprised of wires disposed adjacent and parallel to the lands of the cathode, the wires being round-sectioned and of a diameter consistent with the sizes of the non-emitting areas of the cathode such that the wires are as close to the sides of the electron beams as is compatible with non-interception of the beams by the wires, said cathode and anode being operable at different known potentials and the control grid being operable at a relatively high positive potential, and a screen grid adapted to be maintained during operation of the tube at substantially the same potential as the cathode and comprised of ribbonlike members located radially parallel with the wires of the control grid and having one of their thin edges directed toward the axis of the structure and thereby having their sides extending radially of the axis so as to form at said potential electric fields therearound which aid electron flow to the anode and prevent substantial interception and trapping of electrons between grids.

5. In an electron tube, electrode structures comprising a hollow anode having an inner surface of predetermined radius, a cylindrical cathode coaxial within the anode and having on its outer surface a plurality of axially extending parallel grooves separated by lands, the bottoms of the grooves containing electron emissive material and the lands being non-emissive, the sides of the grooves being free of emissive material and having their surfaces extending radially with respect to the axis of the structure to aid in the proper focusing of electrons from the emissive material into beams directed toward the anode, a control grid comprised of wires disposed adjacent and parallel to the lands, the wires being round-sectioned and of a diameter consistent with the sizes of the non-emitting areas of the cathode such that the wires are as close to the sides of the electron beams as is compatible with non-interception of the beams by the wires, said cathode and anode being operable at different known potentials and the control grid being operable at a relatively high positive potential, and a screen grid adapted to operate at substantially the same potential as the cathode comprised of ribbonlike members located radially parallel with the wires of the control grid and having their flat side surfaces extending radially with respect to the axis of the structure and parallel to the surfaces of the sides of the grooves and forming at said potential electric fields therearound which aid electron flow to the anode and prevent substantial interception and trapping of electrons between grids.
